UNITED STATES PATENT OFFICE.

FRANK PETERSON, OF LYNDEN, WASHINGTON.

SCRUBBING-MACHINE.

1,131,158.

Specification of Letters Patent.

Patented Mar. 9, 1915.

Application filed October 17, 1913. Serial No. 795,792.

To all whom it may concern:

Be it known that I, FRANK PETERSON, a citizen of the United States, residing at Lynden, in the county of Whatcom, and State of Washington, have invented certain new and useful Improvements in Scrubbing-Machines, of which the following is a specification.

This invention relates to improvements in scrubbing machines and has for its object to provide a machine of this class adapted to be moved over the floor by hand during which operation it will automatically scrub the floor by means of a brush which receives water from a spraying device connected to a tank carried by the machine; the machine will also wipe the floor and take up the dirty water and deposit it in a receptacle provided for this purpose and carried by the machine. Means are also provided for increasing or diminishing the friction of the scrubbing brush upon the floor by tilting the machine frame forward or backward.

With the foregoing and other objects in view the invention consists in the combination and arrangement of parts to be herein-after fully described in the following specification, pointed out in the claim and illustrated in the accompanying drawings which form a part of said specification and in which—

Figure 1 is a plan of my improved scrubbing machine. Fig. 2 is a vertical section taken on line 2—2 of Fig. 1. Fig. 3 is a side elevation of the machine.

Like reference characters indicate corresponding parts throughout the several views.

The frame of my machine comprises the sides 1, 1 connected to each other by the transverse braces 2 and mounted upon traction wheels 3 which are connected by axles 4, 4. Upon one of the axles 4 a roller 5 is disposed over which an endless mopping-cloth 6 passes adapted for contact with the floor and which cloth also passes over a small roller 7 disposed near the rear end of the frame and up through the wringer 8, the rollers of which are mounted upon shafts journaled in the sides of the frame. Immediately beneath the wringer 8 a tank 9 is dis-

posed and supported by cleats 10 secured to the sides of the frame and said tank is adapted to receive the water squeezed from the mopping-cloth by the said wringer. In the frame of the machine a reservoir 11 is supported in a suitable manner and said reservoir contains the water to be used to scrub the floor and the same is provided with a faucet 12 through which the water is conducted to a sprayer 13 supported by the frame of the machine at the front end of the same above the rotary scrubbing brush 14 which is supplied with water by said sprayer and which brush scrubs the floor as the machine is drawn over the same by a handle 15 secured to casings 16, 16 carried by the machine and said casings inclose vertical racks 17, 17 located nearer the rear than the front of the machine, each of which carries a shoe 18. Each rack 17 meshes with a cog wheel 19 secured to the frame upon a crank shaft 20 provided with a crank 21 by which said cog wheel is rotated and a dog 22 secured to the frame 1 is adapted for engagement with said cog wheel whereby the same is locked in an adjusted position. The effect of lowering the racks 17 by means of the cogs 19 is to raise the rear wheels of the machine off the floor and depress the front end of the machine increasing the friction of the brush 14 upon the floor thus scrubbing the floor more thoroughly; another advantage of this arrangement is to prolong the use of the scrubbing brush as a worn brush can in this manner be brought in working contact with the floor even though its bristles have been worn at their ends. The end of one of the roller shafts of the wringer is provided with a pulley 23 over which a belt 24 runs that transmits power to said roller shaft from a pulley 25 disposed upon an axle 4 of the traction wheels.

What is claimed is:—

In a scrubbing machine comprising a frame provided with front and rear wheels, a rotary scrubbing brush carried at the front of said frame, vertically movable racks carried by said frame adjacent its rear end, shoes terminally carried by said racks

100

capable of supporting the rear end of said frame and means carried by said frame co-operating with said racks whereby the latter may be depressed to take the weight of the rear end of said frame off the rear wheels.

In testimony that I claim the foregoing

as my own I have hereto affixed my signature in the presence of two subscribing witnesses.

FRANK PETERSON.
